UNITED STATES PATENT OFFICE.

EVERETT G. CLEMENTS, OF WASHINGTON, DISTRICT OF COLUMBIA.

DEVICE FOR MARKING PARKING LIMITS FOR VEHICLES.

Application filed June 29, 1923. Serial No. 648,562.

To all whom it may concern:

Be it known that I, EVERETT G. CLEMENTS, a citizen of the United States, residing at Washington, in the District of Columbia, have invented certain new and useful Improvements in Devices for Marking Parking Limits for Vehicles; and I do hereby declare the following to be a full, clear, and exact description of the invention, 5 such as will enable others skilled in the art to which it appertains to make and use the same.

My invention relates broadly to improvements in street traffic indicators and more particularly to such traffic indicators as are employed to mark the limits of zones prohibiting parking of road vehicles.

In most of our cities police regulations prohibit the parking of road vehicles within 20 certain given radii of fire hydrants, entrances to public buildings, etc. Restricted parking areas are also often provided a given distance from street corners in business districts and at other strategic places 25 for the safety of pedestrians.

Heretofore the limits of such zones have been but poorly indicated, when marked at all. Portable pedestal signs bearing the words "No parking between these signs" or 30 "No parking to corner," etc., and white striping on the curbing and street have been the only parking limit indicators employed. Such modes of marking and indicating the limits of restricted zones have failed to prevent encroachment on and crowding of the 35 limits of such areas by drivers of vehicles, when parking. This violation of traffic regulations has been due largely to inadequate indicators, as the types heretofore referred 40 to depend for their efficiency solely upon their visibility.

To obviate the draw-backs previously referred to and provide an indicator of simple design and efficient and reliable usage, I 45 combine with the usual visible indicator means whereby physical indication will be appreciated by the driver of a vehicle who violates the limits of such a restricted zone.

It is therefore the primary object of my 50 invention to provide a permanent indicator for marking the limits of zones prohibiting parking of road vehicles, which will be visible to the driver of road vehicles and its purpose readily comprehended thereby and adapted to give physical warning that the 55 limit of a restricted area has been encoun-

tered, if unnoticed by the driver, by so positioning an indicator as to actually obstruct the free movement of the vehicle beyond the limits of said area. 60

A further object of my invention is to provide a device of this character adapted to be readily positioned and attached to street curbings and gutters of conventional design. 65

A still further object of my invention is to construct and so position a device of this character as to provide the minimum resistance to water flow in a gutter in which it is located, and to permit the cleaning of 70 such gutter, by sweeping, etc., without laterally moving the indicator from its fixed position.

It is also an object of my invention to provide a device of this character which will 75 be simple and inexpensive in construction and positive and reliable in operation, all as will be hereinafter more fully described and claimed.

Referring to the accompanying drawings 80 which are made a part of this specification, and in which similar reference characters indicate similar parts:

Fig. 1 is a perspective view illustrating 85 one form of my invention as it is intended for use in marking limits of restricted zones at fire hydrants.

Fig. 2 is a vertical transverse section taken on the line 2—2 of Fig. 1, showing the interior of the raised grating and its curb 90 attaching means.

Fig. 3 is a transverse section, similar to Fig. 2, showing a modified form of my invention, permitting the grating to be swung vertically relative to the curb engaging 95 means, and also showing means for adjusting the base of the grating relative to the surface of the gutter.

Fig. 4 is a top plan view of the modification illustrated in Fig. 3. 100

Fig. 5 is a front elevation of a further modified form of my invention illustrating the curb attaching means which permits the grating to be swung vertically, as shown in dotted lines. 105

Fig. 6 is a side elevation, partly in section, of the modification shown in Fig. 5.

Fig. 7 is a vertical sectional view of a grating made in accordance with my invention, showing the curbing cut away immediately behind the grating to permit the installation of illuminating means, and 110

Fig. 8 is a still further modified form of my invention illustrating my marker formed integral with the curbing or as a solid masonry unit secured thereto. In this figure 5 the marker is intended to indicate the limit of a parking zone at street corners.

In the drawings the portions indicated as A represent the usual street or highway gutter and B the sidewalk curbing. Both of 10 these elements, as shown, with the exception of the modification, illustrated by Fig. 8, may be of any well known or approved design or construction permitting the use of my invention in conjunction therewith and 15 need no particular description hereinafter.

In Figs. 1 to 7, inclusive, my invention is illustrated as an arcuate grating 1, preferably formed of metal, such as cast iron, and constitutes a vertical curbing engaging 20 plate portion 2 from which grating bars 3 extend outwardly and downwardly in arcuate form to a semi-circular, horizontally extending base support 4. The curbing engaging portion 2, as illustrated in Figs. 1 25 to 4, inclusive, includes a plate portion 5 extending at substantially right angles thereto and adapted to rest on the upper surface of the curbing B and embrace the outer edge thereof. Warning indication 30 such as the word "Stop" may be embossed or otherwise displayed on the surface of plate 5 as is indicated at 6, and apertures 7 and 8 formed therein for the insertion of expansion bolts to anchor the grating in fixed 35 relation with the curbing B and gutter A.

The base portion 4 constitutes a semi-circular ring extending horizontally from the lower extremity of the curbing engaging portions 2 and is formed on its under surface 40 with a series of spaced supporting feet 9. In Figs. 3 and 4 the supporting feet 9 are shown capable of adjustment for the purpose of levelling the grating 1 on gutters having an uneven surface and to this 45 end bosses 10 are formed on the inner surface of the semi-circular base portion 4 between two adjacent arcuate bars 3 through which bolts 11 are threaded.

It is also desirable under some circumstances 50 to construct the device in such a manner that the grating 1 may be readily swung out of the gutter when sweeping or otherwise cleaning the streets, and permit the grating to be returned to its initial position in the gutter. In Figs. 3 and 4 I have shown the vertical curbing engaging plate 2 connected to the horizontally disposed indicator plate 5 by hinged portions 55 12. The indicator plate 5 being rigidly secured to the upper surface of the curbing B by expansion bolts or otherwise, permits the grating 1 to be readily swung vertically about the axis of the hinged portion 12 out of the gutter A and onto the upper side of 60 the curbing B, as is shown in dotted lines in 65

Fig. 3. In cases where the indicator plate 5 is not employed as a portion of the device, such as in Figs. 5 and 6, the curbing plate 2 may be provided with a lateral extension 13 through which a bolt 14 extends 70 into the side of the curbing to secure the grating in proper position in the gutter A with relation to the curbing B. The grating 1 is thus adapted to be swung horizontally out of the gutter on the bolt 14 as a 75 pivot, when it is desired to temporarily remove the device from the gutter as is clearly shown in dotted lines in Fig. 5. A stop 15 forming a lateral extension of the portion 13 is adapted to support the grating 80 1 in raised position. In Fig. 7 the curbing B is shown cut away immediately behind the grating to provide a mounting for an illuminating means such as an electric bulb indicated at 16, the purpose of which will be 85 readily understood.

The zone marker heretofore described comprises a raised grating 1, preferably formed of metal and constitutes an article of manufacture adapted for ready attachment to curbings such as are in general use. 90 In Fig. 8 I have shown my invention as constituting a rigid portion of the curbing B and gutter A and in this form the marker may be constructed of stone, concrete, etc., 95 and the gutter A widened if desired at this point, as is clearly shown in this figure.

In use the marker forming the subject matter of my invention is intended to form a rigid and permanent indicator of the 100 limits of zones prohibiting parking of road vehicles and as such is adapted to be formed integral with or as an attachment to curbings and gutters of street highways adjacent which road vehicles are required to park by 105 law.

The purpose of my invention is to provide a device which will give physical warning to drivers of road vehicles upon encountering my raised marker, when due to carelessness, inadvertence, or darkness, they have violated a restricted zone, whereupon the vehicle will be backed a sufficient distance to clear the limits of the zone.

As police regulations require that vehicles 110 be parked a given number of inches from curbings of street highways, it is obvious that my marker will extend across the gutter a sufficient distance to obstruct free passage of a vehicle if unnoticed. The raised 115 surface of the marker is preferably formed arcuate as is clearly shown in the drawings, whereby the impact due to encountering same will not in any way damage the vehicle or its occupants. It will also be noted, by 120 reference to the drawing, that the marker is shown as an arcuate grating, spaced from the surface of the gutter by feet so as to permit water flowing in the gutter to pass 125 therethrough unobstructed.

What I claim is:

1. A vehicle parking indicator for street highways comprising a member fixed in position adjacent an edge of the highway and having an arcuate wheel-abutting surface adapted to protrude laterally into the highway.
2. A parking limit indicator comprising a raised grating having gutter and curbing engaging portions.
3. A parking limit indicator comprising a raised grating having gutter engaging portions and portions adapted for attachment to the curbing.
4. A parking limit indicator comprising a raised grating having means for attachment to street curbings whereby said indicator may be swung into or out of the gutter.
5. A parking limit indicator comprising an arcuate marker having substantially flat gutter and curbing engaging portions.
6. A parking limit indicator comprising a raised grating adapted to embrace an edge of the street curbing and extend into the gutter.
7. A parking limit indicator comprising a raised grating having an angular curb-engaging portion and an arcuate portion adapted to extend into the gutter.
8. In combination with a street curbing and its gutter, a parking limit indicator comprising an obstructive element mounted against lateral movement in said gutter and adjacent said curbing.
9. In combination with a street curbing and its gutter, a raised indicator mounted ad-
10. An indicator for marking the limits of zones prohibiting parking of road vehicles comprising a grating having ground and curb-engaging portions and raised portions adapted to obstruct free passage of a vehicle thereover.
11. A device for zoning areas prohibiting parking of road vehicles comprising in combination with a street curbing means having an arcuate wheel-abutting surface fixed against lateral movement relative to said curbing for obstructing free and uninterrupted passage of a vehicle thereover.
12. A parking limit indicator comprising a member secured to the curbing and extending laterally therefrom over the adjacent gutter, substantially as described.
13. A parking zone marker and indicator for street highways comprising a pair of independent obstructive elements fixed relative to each other adjacent the highway curbing to designate said zone therebetween and adapted, while in operative position to permit the passage of a vehicle thereover, substantially as described.
14. A device for indicating the limits of zones prohibiting parking of vehicles adjacent the curbing of street highways comprising slightly elevated means fixed against lateral movement at the limits of said zones and adapted, while in operative position, to permit passage of a vehicle thereover.

In testimony whereof I affix my signature.
EVERETT G. CLEMENTS.
